UNITED STATES PATENT OFFICE.

JOSEPH ALGER, OF BROCKTON, MASSACHUSETTS.

BOX-COVERING MACHINE.

No. 820,166.

Specification of Letters Patent.

Patented May 8, 1906.

Application filed May 10, 1904. Serial No. 207,235.

to all whom it may concern:

Be it known that I, JOSEPH ALGER, a citizen of the United States, residing at Brockton, in the county of Plymouth and Commonwealth of Massachusetts, have invented certain new and useful Improvements in Box-Covering Machines, of which the following is a specification.

This invention relates to machines for covering paper boxes, and particularly to that class of machines in which the covering-paper is applied in a single blank to the bottom and folded about the sides of the box to paste the same in place.

It has been difficult heretofore with any of the machines in use to apply the paper neatly and evenly and also to arrange machines for the great varieties of shape and size for which demand is made.

The object of the present invention is to produce a machine which will not only afford a superior and satisfactory means of performing this somewhat difficult operation, but which will be capable of handling boxes of various sizes and shapes and may be easily and profitably adapted to the various styles of work within the short time available on small rush orders of odd patterns.

To this end the present invention contemplates the employment of certain arrangements and movements of parts and the use of certain adjustments and substitutions of members by which plain or extension-edge boxes may be covered and accommodated, though of differing length, breadth, or depth, and whether the covering-paper is to be applied as a close-fitting sheet, as in the extension-edge box, or as a loose-fitting wrapper, as in the type of box known as the "package end." The particular means by which these results are accomplished will be more fully described in the specification following and the accompanying drawings, in which like letters of reference indicate corresponding parts throughout, and in which—

Figure 1 is a general perspective view of the machine; Fig. 2, a central section through the side-folder in its open position; Fig. 3, a similar section through the side-folder swung up and the roll-slide depressed. Fig. 4 is a perspective detail of the end-turner; Fig. 5, a detail of the edge-turning roll; Fig. 6, an end view of the removable block-sections for an extension-edge box; Fig. 7, a view of similar parts for a plain box, and Fig. 8 is a rear view of the turner shown in Fig. 4.

A is a bed having any suitable means of support, as legs A', upon which bed are brackets B, slidably mounted in grooves a and adjustably held by bolts b in slots in the bed-plate A. The brackets B have on their inner faces shoulders B', (see Figs. 2 and 3,) to which is removably secured by screws a block which forms the support for the box and covering-paper when they are in place to be operated upon. Hinged to each of the brackets B is a side-folder D, to which is removably secured by screws a block E. The folder D is slotted at d, and adjustably mounted therein is a slide F, which consists of the slide portion proper, and adjustably bolted thereto by a bolt f' and a slot f'' is a bracket F', upon which is pivoted an arm G, carrying a roll g at its inner end. This roll is normally pressed against the inner face of the block E by a spring G' pressing against the opposite end of the arm G. The spring G surrounds and is guided by a bolt g', mounted in the bracket F', and acts between said bracket and said opposite end of G. The rolls g are short sectional members strung on an adjustable bolt, on which they turn. By removing or adding these sections the total length of the roll proper may be varied to meet the requirements of the box. y² represents a pair of lock-nuts upon the end of the bolt g', which limit the extent of the movement of the roll g' on the block E or hold it away from said block altogether, according to the thickness of the box side over which it must pass. The slide F is normally held out or away from the box-support to which the folder is hinged by a spring F'.

H is an arm adjustably mounted, by means of set-screws and collars, on the shaft J. 95 This arm has pivoted at h a blade H', which is extended to the rear and continued in a shank H'', which a spring h² normally keeps pressed inward to direct the plate H' slightly outward to clear the edge of the box in its movement forward to turn the paper about the end of the same. The arm H is held in a backward position by the spring X, which is fastened at one end to the arm and at the other to one of the collars. The arm is operated by contact with the block I², against which it is yieldingly held by the spring X.

I is a plunger normally held out by the spring i and located in the block I². This block is adjustably mounted upon and is connected to the folder D by a screw and slot.

K is a screw having lock-nuts k and is

tapped through a block Y, which is adjustably mounted on the pivot p. This screw has a conical point K', which engages the end of the plunger I as the slide F descends in its slot to press in said plunger and bear upon the end H² of the turner H' to tip the same and press it against the end of the box.

Fixed upon the shaft J above mentioned is a bell-crank L, which is connected by a link L' to the side-folder D and by a second link L² to a slide M. The slide M is slotted at m and carries a stud N, which is adjustable along said slot m. The link L is also slotted at its lower end, as indicated at l, and said stud N passes through said slot l, so as to loosely slide in the same. It will be readily seen by the drawings, Fig. 1, there are two slides M, each connecting at opposite sides by pairs of links to the side-folders and roll-slides. The structure and function of these sides are the same, so that in this description only one need be described. The operation of the side-folders is in pairs and is identical, so that in the description only one folder or set of folders need be considered. It may be well to state, however, at this point that the folders on the long side of the box are accompanied in their action by the end-turners, which are not present in connection with the short side-folders, (or, perhaps more properly speaking, end-folders.)

O is a spring connection between the link L² and the stud N to normally hold said stud against the upper end of said slot l. This spring has the function of allowing the folder connection to yield to allow the slide M to continue in its downward path and secure the necessary straight pull down on the roll-slide, and also it acts as a general safety device in allowing the yielding of the parts in case the side-folders get jammed.

P is a second link pivoted at p to the roll-slide F at one end and at the other end being also slotted at p' to receive the stud N, which also works loosely in said slot. The slide M works on a rod Q and is operated by treadles R and adjustable connections R', said parts being normally held in a raised position by the springs S.

Y is a guide-rod for the slides M to prevent their swinging about the rod Q.

In Fig. 6 a part of the brackets B are shown as supporting a block C. This is preferably a plain block cut to fit the bottom of the box to be covered, and as the same may be of soft wood it can be easily and quickly prepared of any size which may be required. The blocks E are preferably likewise of wood and are usually supplied in strips which may be sawed into the proper lengths to fit the sides of the box. There are two general types of boxes which are covered in this machine—the extension-edge box, as indicated in Fig. 6, and the plain box, as indicated in Fig. 7. The box is indicated in place in Figs.

1, 2, and 3 and in said last two named figures is shown as an extension-edge box. If a plain box is to be covered, a block of the thickness indicated in Fig. 7 at C' is employed, which rises to the level of the hinges 70 of the side-folders. The side-folding blocks E' in this case are plain blocks which merely meet the edge of the box C' when the folder is swung up. As shown in Fig. 6, the block C, which supports the extension-edge box, is 75 slightly thinner than the box C' and does not rise to the level of the hinge, but leaves a depressed surface which corresponds to the thickness of the extension-bottom. In this case when the folders are open the hinges 80 form about said support a ridge which aids in centering the box thereon. With the extension-box, moreover, the side blocks E are made slightly thicker, as indicated by the dotted line e in Fig. 6, which thickened portion accommodates the extension edge and bears down upon the same with its lower face and against the side of the box with its side. As stated above, these blocks can be easily prepared of any length, breadth, or 90 thickness to accommodate boxes of any length, depth, or with or without extension edges.

The operation of the machine is as follows, it having been adjusted to the size of the box 95 to be covered and being provided with suitable blocks. The operator places a box, to the bottom of which a covering-sheet has been attached, upon the box-support C. The treadle is then depressed, which controls 100 the slide M, to which the side-folders are connected. As this slide M descends it draws through the link and spring connection O upon the bell-crank L to throw up the side-folders against the side of the box, thus pressing the paper in place. The end-turner H' 105 at the same time is swung forward by the engagement of the block I' on the side-folder therewith to bring the covering-paper around the corner of the box and, if the same is not a flapped blank, to give it the proper fold, so that it will not wrinkle when the end-folder rises. As soon as the side-folder has swung up snugly against the box and the end-turner has reached its utmost position the link P, having been brought up to a vertical position 110 by the upward swing of the folder, will be caught at the bottom of its slot p' by the stud, and as the treadle continues to descend the spring O yields to allow the stud N to move down in the slot l, and the link P will be drawn down to move the roll-slide F in its slot. As this slide moves down in its slot the roll g encounters the edge of the box and that portion of the covering-paper which extends above the same and which is to be turned in. At this point the spring G' yields 115 to allow the roller to ride over the edge of the box, at the same time firmly pressing it against the same to paste the paper against the inside 120 125 130

of the box, as above indicated. As the slide F descends the conical point K' of the screw K, which is mounted thereon, meets the end of the plunger I, and as it passes by the same it 5 presses it in and against the end of the lever H² to tip the plate H¹ and press it firmly against the end of the box, thus making certain the adhesion of the paper to the box. As the treadle is released it is returned by the spring 10 S and the parts resume their normal position in the reverse of the order above named. The second treadle is now depressed, which moves the slide M', which controls the folders at the end of the box. The movement of the parts here is the same, except that there is no end-tuner and that in covering a package-end box the folder has extra thickness of paper with which to deal.

The folders of this machine may be otherwise mounted than as shown, and the parts may be variously operated and connected. Various parts may also be omitted and obvious mechanical equivalents may be substituted without departing from the spirit of 25 my invention.

The machine may be operated by treadles, as shown and described, or connected suitably to a power-shaft. The removable blocks may also be given various shapes and cut to 30 various sizes and may be furnished in regular sets or made for the machine, as circumstances require.

What I therefore claim, and desire to secure by Letters Patent, is—

35 1. In a machine for covering paper boxes, a support for the box and covering-paper, side-folders hinged to said support, rolls slidably mounted upon said side-folders, means to swing said folders into position, a second 40 means to operate the rolls, and a single means to furnish movement to said folder and said roll-operating means successively and a yielding connection between said means to furnish movement and said folder-operating means.

45 2. In a machine for covering paper boxes, a support for a box and covering-paper, side-folders mounted to be moved relatively thereto to fold and press said paper against the side of said box, rolls movably mounted upon said side-folders and means to move said rolls over the inner face of said folders to press the paper against the inside of the box.

50 3. In a machine for covering paper boxes, a support for the box and covering-paper, side-folders mounted to be moved relatively thereto to fold and press said paper against the side of said box, spring-pressed rolls movably mounted upon said side-folders and 55 means to move said rolls over the inner face of said folders to press the paper against the inside of the box.

4. In a machine for covering paper boxes, a support for the box and covering-paper, side-folders mounted to be moved relatively

thereto to fold and press said paper against the side of said box, adjustable rolls movably mounted upon said side-folders and means to move said rolls over the inner face of said folders to press the paper against the 70 inside of the box.

5. In a machine for covering paper boxes, a bed carrying a removable box-support, adjustably-mounted side-folders carrying removable folder-blocks, and extensible edge-turning rolls movably mounted upon said side-folders.

6. In a machine for covering paper boxes, a bed carrying a removable box-support, adjustably-mounted side-folders carrying removable folder-blocks, and spring-pressed extensible edge-turning rolls movably mounted upon said side-folders.

7. In a machine for covering paper boxes, a bed carrying a removable box-support, adjustably-mounted side-folders carrying removable folder-blocks, and spring-pressed extensible edge-turning rolls movably mounted upon said side-folders, said rolls being adjustable.

8. In a machine for covering a paper box, a support for the box and covering-paper, side-folders hinged to said support, edge-turning members slidably mounted upon said folders, a reciprocating slide to move said parts, links connecting said slide, and the folders and edge-turning members, said folder-link including a yielding connection.

9. In a machine for covering paper boxes, a support for the box and covering-paper, side-folders hinged to said support, edge-turning members slidably mounted upon said folders, a reciprocating slide to move said parts, slotted links connecting said slide, and the folders and edge-turning members, and a spring to retain the said slide at the upper end of the slot of said folder-links.

10. In a machine for covering paper boxes a support for the box and covering-paper, side-folders hinged to said support, edge-turning members slidably mounted upon said side-folders, a reciprocating slide to move said parts, a stud on said slide, links connecting said slide and the folder and edge-turning members, said links being slotted to move 115 thereon and yielding means to restrain the movement of the stud in the folder-link.

11. In a machine for covering paper-boxes, a support for the box and covering-paper, side-folders hinged to said support, rolls slidably mounted upon said side-folders, a reciprocating slide to remove said part, said slide having a stud, a link operatively connecting said slide and the folder member, said link being slotted to inclose the said stud, and a 125 yielding connection between said link and said slide.

12. In a machine for covering paper boxes, a support for the box and covering-paper, side-folders hinged to said support, rolls slid-

- ably mounted upon said slide-folders, a reciprocating slide to move said parts, links connecting said slide and the folder and roll members, said folder-member link having a yielding connection to said slide whereby said slide may continue to move to operate the roll member.
13. In a machine for covering paper boxes, a support for the box and covering-paper, side-folders hinged to said support, edge-turning means slidably mounted upon said side-folders, a reciprocating slide to move said parts said slide having a stud, a link operatively connecting said slide and the folder member, operative connections between said slide and roll members, said folder-member link being slotted to receive said stud and having a yielding connection to said slide whereby said slide may continue to move to operate the roll member after said folder member is closed.
14. In a machine for covering paper boxes, a support for a box and the covering-paper, side-folders hinged thereto, edge-turning means slidably mounted on said side-folders, a spring for pressing said means against the face of said side-folders, means to close the folder and means to operate the edge-turning member.
15. In a machine for covering paper boxes, a support for the box and covering-paper, side-folders hinged thereto, turning-rolls slidably mounted on said side-folders, a reciprocating slide, means connecting said slide and side-folders, to operate the latter, means connecting said slide and the turning-rolls to move said rolls on said side-folders, said folder-connecting means including a yielding member to permit the complete movement of the slide.
16. In a machine for covering paper boxes, a support for the box and covering-paper, side-folders hinged thereto, edge-turning members slidably mounted on said side-folders, means to yieldingly press said members against the face of said folders, a reciprocating slide, means connecting said slide and said side-folders, to operate the latter, means connecting said slide and said edge-turning members to move said member on said side-folder, the folder connecting means including a yielding member to permit the complete movement of the slide.
17. In a machine for covering paper boxes, a support for the box and covering-paper, side-folders hinged thereto, edge-turning members slidably mounted on said slide folders, a reciprocating slide, a stud on said slide, a link having a slot embracing said stud and connecting said slide and side-folder, yielding means to hold said stud in the upper end of said slot, and a link having a slot also embracing said stud and connecting said slide with said edge-turning member.
18. In a machine for covering paper boxes, a support for the box and covering-paper, side-folders hinged thereto, edge-turning members slidably mounted on said side-folders, a reciprocating slide, a slot in said slide and a stud adjustably mounted in said slot, a link having a slot embracing said stud and connecting said slide with said side-folder, yielding means to hold said stud in the upper end of said slot, and a link having a slot also embracing the said stud and connecting said slide with the edge-turning members.
19. In a machine for covering paper boxes, a bed carrying a stationary, removably, mounted support for the bottom of the box and covering-paper attached thereto, adjustable side-folders having removable folder-blocks, mounted to swing relatively thereto to fold and press the covering-paper against the box, and means mounted on said side-folders to turn the paper over the edge of the box.
20. In a machine for covering an extension-edge box, a bed carrying a removable support for the box and covering-paper, adjustable side-folders mounted to move relatively thereto, to fold and press the covering-paper against the box, and removable folder-blocks mounted on said side-folders having portions to press the covering-paper against the side of the box and against the extension edge of the box.

In testimony whereof I affix my signature in presence of two witnesses.

JOSEPH ALGER.

Witnesses:

WILLIAM G. ROWE,

LOYED E. CHAMBERLAIN.
